UNITED STATES PATENT OFFICE.

WILLIAM MORTINER RAWL, OF LYKESLAND, SOUTH CAROLINA.

MAIL-TYING DEVICE.

Application filed January 25, 1923. Serial No. 614,894.

To all whom it may concern:

Be it known that I, WILLIAM M. RAWL, a citizen of the United States, residing at Lykesland, in the county of Richland and State of South Carolina, have invented certain new and useful Improvements in Mail-Tying Devices, of which the following is a specification, reference being had therein to the accompanying drawing.

10 This invention relates to package tying devices and more particularly to that class of devices which are specially adapted to tying packages of letters.

For many years mail has been tied with an ordinary jute string which was thrown away when the package was opened, thus, causing a waste amounting to thousands of dollars each year, and it has long been the aim of inventors to obtain a device which was not only as conveniently operable and effective as the ordinary string, but a device which was also as inexpensive and yet could be used repeatedly before it had to be discarded. To my knowledge no such device has yet been devised, although many have been adopted and subsequently discarded, either on account of the fact that they were impractical from the standpoint that they could not be secured upon the package with as much facility as the ordinary twine, or that their cost was prohibitive.

It is, therefore, the object of this invention not only to avoid the difficulties which have been encountered in previous devices of this character, but also to produce a device which can be utilized with facility equal to the application of ordinary twine and at the same time which is no more expensive.

It is also the object of this invention to provide a device equally as inexpensive as the ordinary twine which does not have to be discarded after each use, but which may be continuously used for a long period of time.

Still another object of the invention is the provision of a device embodying a flexible member which enables the operator to start his tying operation from either end thereof, thereby conserving time and eliminating the necessity of starting from a particular end, and in a particular manner which fault is inherent in most of the devices which have been heretofore adopted.

Further objects of the invention will appear as the following specification is read in connection with the accompanying draw-

ing which forms a part of this application, and in which:

Fig. 1 is a perspective view, partly broken away showing the completed device; 60

Fig. 2 is a plan view of a package of letters showing in diagram the first operation in applying the device;

Fig. 3 is a similar view showing the package of letters completely tied with the device, and 65

Fig. 4 is an edge elevation of a completely tied letter package.

The device as illustrated in Fig. 1 is constructed of a single strand of flexible material indicated at 1 which is bent back upon itself forming at one end the bight 2. The opposite or free ends of the member are brought together and tied as shown at 3, and in this stage of the operation of forming the device the flexible member would produce a closed ring or hoop. Separated from the opposite ends, or in other words, from the bight 2 and the knot 3, I tie small knots 4 and 5 which form end loops 6 and 7 and 70 an intermediate loop 8 which may be of any suitable length varying according to the size of packages to be tied.

It is, of course, to be understood that the material used to construct the tying device 85 may be any suitable type of cord or twine although in practice I prefer to use a twisted or braided cord of long fiber cotton or hemp which has in addition to great strength, long wearing qualities, and which 90 is to a large extent proof against cutting by abrasion. By using a material of this character which is very little if any, more expensive in large quantities than the ordinary jute twine employed at the present 95 time, I am able to produce a device with which packages of letters may be rapidly tied very firmly and securely without cutting the cord, and which device may be utilized many times before it becomes so worn 100 as to necessitate discarding.

In the use of the device the operator grasps either end of the device with his left hand, and the opposite end of the device with his right hand, he then inserts the end 105 of the device held in his right hand through the large loop 8 as shown in Fig. 2, and pulls this end until a tight loop is formed around the package. Holding the package with the left hand and preferably with the thumb 110 over the loop 9, where the body of the device passes through the loop 8 he wraps the

portion of the device, between the knots 4 and 5, around the package one or more times, and then inserts the free end between the letters of the package. The frictional contact of the letters holds this free end securely against displacement until it is desired to untie the package. When the package is to be untied the operator pulls the free end from between the letters and then 10 grasps the opposite loop 6 or 7 and by pulling upon the same, completely unties the package and at the same time automatically causes the removal of the strands from the loop 8 so that the device is in its normal 15 position and ready for re-use.

If desired, after the loop 9 has been formed only one wrap may be taken around the package and the free end inserted between the letters at one side of the package 20 and then carried over and inserted between the letters at the opposite end of the package, giving a double frictional grip upon the free end and thereby doubly insuring the maintenance of the parts intact until untying is necessitated.

It will be noticed that in the use of the

device as thus described, that the operator may start with either end of the device, and that the end which he starts with forms in effect a handle for holding the device when the opposite end is placed through the large loop and for grasping to remove the device from the package when the free end has been removed from between the letters.

I claim:

A package tying device comprising a single flexible strand having its terminals connected together to produce a loop and its sides brought together to form parallel strands said strands being connected together adjacent opposite ends of said loop to produce short end loops used as handles and a long intermediate loop through which either handle loop may be passed to produce a slip loop around the package to be tied.

In testimony whereof I affix my signature in the presence of two witnesses:

WILLIAM MORTINER RAWL.
